UNITED STATES PATENT OFFICE.

JOSEPH F. McCARTHY, OF PHILADELPHIA, PENNSYLVANIA, ASSIGNOR OF ONE-HALF
TO W. T. BROWN, JR., OF PHILADELPHIA, PENNSYLVANIA.

SIGNAL APPARATUS FOR ELEVATORS.

1,097,344.

Specification of Letters Patent. Patented May 19, 1914.

Application filed June 13, 1912. Serial No. 703,520.

To all whom it may concern:

Be it known that I, JOSEPH F. McCARTHY, a citizen of the United States, residing at Philadelphia, county of Philadelphia, and State of Pennsylvania, have invented certain new and useful Improvements in Signal Apparatus for Elevators, of which the following is a specification.

This invention generally speaking, relates to indicators or signals for elevators and has more particular relation to electrically controlled up and down signal lamps for designating at each hall or floor of a building, the approach up and down, of an elevator car or cage, and has for its principal object the providing of a novel form of commutator for accomplishing this purpose.

A further object may be said to reside in the utilizing of what is termed the dial system of signaling, for operating an up and down electrical flash system.

A further object of the present invention resides in the providing of a special construction of parts, operated by a mechanical dial mechanism for illuminating or flashing the up and down lamps of the electrical signal, to give notice of an approaching car one or more floors in advance of arrival at a given floor.

A still further object of the present invention is to provide an electrical signaling apparatus of simple, effective and comparatively inexpensive construction and of positive operation for elevators, which shall work in conjunction with a mechanical dial located upon each floor of a building, whereby the progress of the car either up or down is flashed by the electrical apparatus at each floor in advance of the approach of the car.

A still further object of the present invention is to provide a novel construction of make and break contact device and its means of actuation, which may be operated successfully in connection with dial systems now in use or may be used independently thereof.

With these and other objects in view, the invention consists of the improvements hereinafter described and finally claimed.

The nature, characteristic features and scope of the invention will be more fully understood from the following description taken in connection with the accompanying drawings forming part hereof and in which:

Figure 1, is a fragmentary view in front elevation, for the purposes of illustration, of

a combined mechanical and electrical signal device shown in application to the grille work of an elevator shaft, Fig. 2, is a top or plan view, drawn to an enlarged scale, of the combined mechanical and electrical signal device, shown in Fig. 1, Fig. 3, is a view in section, taken upon the line 3-3 of Fig. 1, but drawn to an enlarged scale, Fig. 4, is a fragmentary view in side elevation of the combined mechanical and electrical signal device, Fig. 5, is a view in front elevation of the commutator cylinder, and Fig. 6, is a view in front elevation of the make and break contact device shown in the foregoing figures.

In elevator signaling apparatus, it has been customary in the past in some places to provide an equipment known as the dial system, which is mechanically operated and which is designed to designate at each floor, by means of pointer and dial, the exact location of an elevator car. Modern equipment of elevator systems, however, has to a great extent supplanted the mechanical system with electrical flashes to designate the up and down movement of an elevator car. To remove the mechanical dial system and install the electrical flash system entails considerable expense, particularly in that the ordinary flash system constitutes a complicated series of electrical circuits and coöperating switches.

The present invention aims among other things to utilize the present mechanical dial system of elevator signals and use in conjunction therewith, by operatively connecting thereto so as to be operated thereby, an electrical flash system. By this arrangement and by the particular construction of parts hereinafter to be recited, it is possible whenever dial systems are installed, to add at very small cost the electrical flashes without, however, the installation of a system of circuits and coöperating switches of intricate and complicated nature. It is to be remarked at this time, however, that the novel form of commutator and make and break device of the invention may be used to operate an up and down flash independently of the dial and pointer.

Referring now to the drawings and more particularly to Fig. 1, the improved apparatus and system of the invention is shown as being arranged in position on the grille work of the elevator shaft of a building

immediately above that portion of the elevator shaft opening before which the elevator car stops. A description will first be given of the dial, which is mechanically operated and which for the sake of illustration will be assumed to have been previously installed. The dial 10, which is usually constructed of metal, is provided with numerals, arranged consecutively, designating the various floors of a building. Disposed horizontally with respect to the dial 10, and having the smaller end 11, thereof penetrating, the dial 10, is a shaft 12, having a pointer 13, thereon, which is adapted to travel back and forth around the dial 10. The opposite end of the shaft 12, has fixed thereto a grooved pulley 14, around which passes an operating belt 15, partial rotation to which is imparted in the up and down movement of the elevator in the well understood manner. The above described parts may be of ordinary and well understood construction. Assuming now that a building having such a dial system is to be equipped with an electrical flash system, the above parts may be readily utilized for operating the flash system, a description of which will now be given. Shown as encircling the shaft 12, is a metallic sleeve 16, having a flanged portion 17, which flanged portion is secured to the rear of the dial 10, by means of screws 18. The sleeve 16, is insulated from the shaft 12, by suitable insulating material 19. Loosely mounted upon the sleeve 16, so as to be relatively movable around its own axis is a make and break device or switch lever 20, see Fig. 6. Upon opposite sides of this device 20, are rings 21, and 22 usually of fiber on account of the wearing qualities thereof. As shown in Fig. 3, the inner end of the sleeve 16, or that end which is opposite to the flanged end, is screw threaded as at 23, for the reception of an adjusting nut 24. Interposed between the nut 24, and the ring of insulating material 21, and coiled around the sleeve 16, is a tension spring 25. This spring 25, serves to force the ring 21, device 20, and ring of insulating material 22, up against the flange 17, of the sleeve 16, so as to properly position the said make and break device. As clearly shown in Figs. 3, and 6, the said device 20, is apertured as at 26, for the passage therethrough of a member 27, which is held in constant contact with and tracks upon the flange 17, of the sleeve 16, by virtue of a leaf spring 28. The free end of the make and break device or switch lever 20, has fixed thereto a horizontally disposed contact stud 29, having an enlarged head, extending from which are platinum contact pins 30. The purpose and operation of the make and break device including its complemental contact stud will presently appear. Having fixed relation with

the shaft 12, is a commutator cylinder 31, which is shown as being located between the grooved pulley 14, and the free end of the sleeve 16. This commutator cylinder 31, is equipped with suitably spaced contact plates 32, and 33, of which the contact plate 32, is designed to correspond with the up signal and of which the contact plate 33, is designed to correspond with the down signal, which signals will be hereinafter described. Shown as extending from the side 34, of the commutator cylinder 31, are horizontally disposed contact pins 35, and 36. In practice these contact pins 35, and 36, are spaced with respect to each other so as to confine for limited movement therebetween, the hereinbefore described contact stud 29, of the make and break device or switch lever 20. The contact plate 32, is electrically connected by means of a connection 37, with the contact pin 36, and the contact plate 33, is similarly connected by a connection 38, with the contact pin 35. Rigidly fixed to the back of the dial 10, is a brush holder 39, which supports a pair of spring impelled carbon or metal brushes 40, and 40^a. A convenient form of brush is that disclosed in Fig. 5, wherein the brushes 40, and 40^a, are contained within barrels 41, and are normally pressed in the direction of the arrow by means of springs 42, screw threaded caps 43, being present to retain the springs in position. Screws 44, serve to retain the barrels 41, in adjusted position and in addition serve as binding posts to which conductors *a*, and *b*, may be connected. It may be here remarked that conductor *a*, leads from the brush complemental to the contact plate 32, of the commutator cylinder, to one terminal of the lamp that flashes the up signal of the travel of the elevator. Conductor *b*, leads from the brush complemental to the contact plate 33, of the commutator cylinder, to one terminal of the lamp that flashes the down signal of the elevator. In this connection, it will, of course, be understood that the remaining terminals of the up and down lamps are connected by conductors *c*, with the return lead *d*, from the source of current supply. Before leaving the subject of circuit connections, it may be stated that current is supplied from any suitable source by conductor *e*, to an electrical connection 45, upon the back of the dial 10, the electrical connection 45, in turn forming connection with the flange 17, of the sleeve 16, to establish a constant circuit of current thereto. As clearly shown in Fig. 3, the up and down flash lights 46, and 47, are supported by a bracket 48, which is secured to the grille work of the elevator shaft.

A description will now be given of the mode of operation of the above described parts, it, of course, being understood that a

dial and pointer commutator and make and break device are present at each floor. In this connection it will be assumed that the elevator car is at the ground floor of a building as is shown in Fig. 1, and that the apparatus disclosed in Fig. 3, is located upon the second floor of the same building. As the elevator car moves upward the pointer 13, travels in the direction of the arrow in Fig. 1, and the contact point 36, of the commutator cylinder 31, moving with the cylinder abuts against and moves with it the contact stud 29, and the make and break device or switch lever 20, see Fig. 5. Approximately 15 at the same moment the contact plate 32, of the commutator cylinder 31, moves into contact with the brush 40, which lies in its path of movement. Thus, there is immediately established electrical connection to flash up 20 lamp 46, by way of conductor *e*, conducting strip 45, flange 17, of the sleeve 16, contact piece 27, spring 28, switch lever 20, contact stud 29, contact piece 36, connection 37, contact strip 32, brush 40, and conductor *a*, 25 thereby designating to the person before the elevator opening of the second floor that a car is approaching and that it is moving upward. Of course, while the pointer designates that it is going upward, in large office 30 buildings where a series of elevators are present, it is very hard to watch all of the pointers but very easy to notice the flash of a lamp. Assuming that the elevator car still continues upward, the operation of the 35 signal device at the second floor for flashing the up-light at the third floor of the building is a counterpart operation of the signal device at the first floor. Likewise the operations of the remaining signal devices 40 throughout the height of the elevator shaft are counterpart operations of the first described signal device. In this connection it is to be noted that all the signal devices are 45 duplicates of each other and it is the adjusting of each commutator cylinder 31, upon its complementary shaft 11, to agree with the indicator 13, thereof, which times the operation of each signal device. For 50 example, if the building in which the installation of the present invention is being made is a ten story building, each commutator cylinder 31, is adjusted upon its complementary shaft 11, so that it assumes a position advanced one tenth of the circumference 55 of its shaft for each succeeding floor. This advanced position of the commutator cylinder, positions the contact strips 32, and 33, thereof, so that said contact strips are 60 timed to form electrical connection, in sequential relation, with the lighting circuit, floor after floor or in other words every one tenth of the height of the elevator shaft. Assuming now that the elevator car is 65 descending the shaft 12, together with its complementary pointer 13, and commutator

cylinder 31, will rotate in a direction opposite to that just described. It will, of course, be understood that in the descending of the elevator car, it is important that the up light 46, be not flashed and that the down light 47, be operated. As the commutator cylinder 31, moves in the direction of the dotted arrow in Fig. 5, the contact pin 35, moving with the cylinder, abuts against the contact stud 29, thereby moving away from the contact pin 36, said stud 29, which pin in the upward movement of the elevator has been abutting against said contact stud 29. Thus, as the elevator moves downward the commutator cylinder 31, moves around the sleeve 16, the switch lever 20, and practically at the same moment that the contact piece 35, and contact stud 29, contact, the contact piece 33, of the commutator cylinder 31, comes into contact with brush 40^a, which lies in the path thereof. Immediately a circuit is established by way of the conductor *e*, contact plate 45, flange 17, of the sleeve 16, contact piece 27, spring 28, contact piece 35, connection 38, contact plate 33, brush 40^a, conductor *b*, and lamp 57. 70 75 80 85 90

Having now particularly described the invention and its mode of operation, what I claim as new and desire to secure by Letters Patent is:

1. An elevator signal apparatus comprising a set of electrically controlled up and down signal lamps at each elevator landing, a rotatably mounted shaft adjacent each set of signal lamps, a commutator cylinder fixed to each shaft, each cylinder being equipped with a suitably spaced contact plate and a contact pin complementary to each lamp in a single set, mechanical means operative with the movement of an elevator car for partially rotating in either direction all of said shafts, a separate brush for each lamp each brush lying in the path of travel of its complementary contact plate and adapted to electrically control the flashing of said lamps and a make and break contact member in constant circuit with a source of electrical current loosely mounted upon each of said shafts and movably confined between the said contact pins of the commutator cylinders so as to be capable of rotation therewith and form a contact with one or the other of said pins in accordance with the direction of rotation of the respective shafts. 100 105 110 115

2. An elevator signal apparatus comprising a set of electrically controlled up and down signal lamps at each elevator landing, a rotatably mounted shaft adjacent each set of signal lamps, a commutator cylinder fixed to each shaft, each cylinder being equipped with a suitably spaced contact plate and a contact pin complementary to each lamp in a single set, mechanical means operative with the movement of an elevator car for partially rotating in either direction all of 120 125 130

said shafts, a separate brush for each lamp each brush lying in the path of travel of its complementary contact plate and adapted to electrically control the flashing of said lamps, a make and break contact member in constant circuit with a source of electrical current loosely mounted upon and insulated from each of said shafts and movably confined between the contact pins of the commutator cylinders, so as to be capable of rotation therewith and form a contact with one or the other of said pins in accordance with the direction of rotation of the respective shafts, whereby electrical connection is established between one of said contact plates and one of said lamps at every landing at predetermined periods and a tension device for positioning each make and break contact member with respect to its complementary shaft.

3. An elevator signal apparatus comprising a set of electrically controlled up and down signal lamps at each elevator landing, a supporting element adjacent each set of signal lamps, a shaft rotatably carried by each supporting element, a commutator cylinder fixed to each shaft each cylinder being equipped with a suitably spaced contact plate and a contact pin complementary to each lamp in a single set, mechanical means operative with the movement of an elevator car for partially rotating in either direction all of said shafts, a separate brush for each lamp, each brush lying in the path of travel of its complementary contact plate and adapted to electrically control the flashing of said lamps, a sleeve fixed to each supporting element through which said shaft passes and is insulated therefrom said sleeve being in constant circuit with a source of electrical current, a make and break contact member loosely mounted upon each of said sleeves said contact member being movably confined between the said contact pins of the commutator cylinders so as to be capable of rotation therewith and form a contact with one or the other of said pins in accordance with the direction of rotation of the respective shafts, whereby electrical connection is established between one of said contact plates and one of said lamps at every landing at predetermined periods and a tension device for properly positioning thereon said make and break contact member.

4. An elevator signal apparatus comprising a bracket supporting a set of electrically controlled up and down signal lamps at each elevator landing, a supporting element adjacent each bracket, a shaft rotatably mounted with respect to each supporting element, a commutator cylinder fixed to each shaft each cylinder being equipped with a suitably spaced contact plate and a contact pin complementary to each lamp in a single set, a pulley fixed to the outer end of each shaft,

mechanical means connecting each pulley for coöperating with the movement of an elevator car for partially rotating in either direction all of said shafts, a separate brush for each lamp each brush lying in the path of travel of its complementary contact plate and adapted to electrically control the flashing of said lamps said brushes being carried by the various supporting elements, a sleeve fixed to each supporting element through which said shaft passes and which is insulated therefrom said sleeve being in constant circuit with a source of electrical current, a make and break contact member loosely mounted upon each of said sleeves and being movably confined between the commutator contact pins so as to be capable of rotation therewith and form contact with one or the other of said pins in accordance with the direction of rotation of the respective shafts whereby electrical connection is established between one of said contact plates and one of said lamps at every landing at predetermined periods, an adjustable nut carried at the free end of each sleeve and a tension spring interposed between said nut and said make and break contact member for pressing the latter toward the supporting element.

5. An elevator signal apparatus comprising a bracket supporting a set of electrically controlled up and down signal lamps at each elevator landing, a dial having delineated thereon the various floors of a building adjacent each bracket, a shaft rotatably mounted with respect to each dial, a pointer fixed to each shaft for registering with the dial parts, a commutator cylinder fixed to each shaft, each cylinder being equipped with a suitably spaced contact plate and a contact pin complementary to each lamp in a single set, mechanical means coöperating with the movement of an elevator car for partially rotating in either direction all of said shafts, a separate brush for each lamp each brush lying in the path of travel of its complementary contact plate and adapted to electrically control the flashing of said lamps, a sleeve fixed to the rear of said dial through which said shaft passes and which is insulated therefrom, said sleeve being in constant circuit with a source of electrical current, a make and break contact member loosely mounted upon each of said sleeves and movably confined between the said contact pins of the commutator cylinder so as to be capable of rotation therewith and form contact with one or the other thereof in accordance with the direction of rotation of the respective shafts, whereby electrical connection is established between one of said contact plates and one of said lamps at every landing at predetermined periods, an adjusting nut carried at the free end of each sleeve and a tension spring between said adjusting nut and said make and break contact member.

tact member for pressing the latter toward the said dial.

6. An elevator signal apparatus comprising a set of electrically controlled up and down signal lamps at each elevator landing, a rotatably mounted commutator cylinder arranged in juxtaposition to each set of signal lamps, each cylinder being provided with an operatively spaced contact strip and a contact projection complementary to each lamp in a single set, mechanical means operative with the movement of an elevator car for partially rotating in either direction all of said commutator cylinders, a separate brush for each lamp each brush lying in the path of travel of its complementary contact strip for electrically control-

ling the flashing of said lamps, and a rotatable make and break contact medium in constant circuit with a source of electrical current for each of said commutator cylinders movably confined between the contact projections of said commutator cylinders so as to be capable of rotation therewith to form contact with one or the other of said projections governed by the movement of the respective cylinders. 20 25

In testimony whereof I have hereunto signed my name.
